(57) CLAIM

The ornamental design for a sun canopy, as shown and described.

DESCRIPTION

FIG. 1 is a perspective view of a sun canopy showing a new design;

FIG. 2 is a front elevation view thereof;

FIG. 3 is a rear elevation view thereof;

FIG. 4 is a left side elevation view thereof, the right side being a mirror image;

FIG. 5 is a top plan view thereof;

FIG. 6 is a bottom plan view thereof;

FIG. 7 is a cross-sectional view of the sun canopy of FIG. 4 as viewed in the direction of the arrows along line 7;

FIG. 8 is another perspective view of the sun canopy of FIG. 1 showing it installed on an infant/baby lounger for environmental purposes;

FIG. 9 is a perspective view of the sun canopy of FIG. 1 showing an alternate embodiment;

FIG. 10 is a front elevation view thereof;

FIG. 11 is a rear elevation view thereof;

FIG. 12 is a left side elevation view thereof, the right side being a mirror image;

FIG. 13 is a top plan view thereof;

FIG. 14 is a bottom plan view thereof;

FIG. 15 is a cross-sectional view of the sun canopy of FIG.

12 as viewed in the direction of the arrows along line 15;

FIG. 16 is another perspective view of the sun canopy of FIG. 9 showing it installed on an infant/baby lounger for environmental purposes;

FIG. 17 is a perspective view of the sun canopy of FIG. 1 showing an alternate configuration;

FIG. 18 is a front elevation view thereof;

FIG. 19 is a rear elevation view thereof;

FIG. 20 is a left side elevation view thereof, the right side being a mirror image;

FIG. 21 is a top plan view thereof;

FIG. 22 is a bottom plan view thereof;

FIG. 23 is a cross-sectional view of the sun canopy of FIG.

20 as viewed in the direction of the arrows along line 23;

and,

FIG. 24 is another perspective view of the sun canopy of

FIG. 17 showing it installed on an infant/baby lounger for environmental purposes.

The broken line showing of an infant/baby lounger in FIGS.

8, 16 and 24 illustrates environmental subject matter. The remaining broken lines in the drawings illustrate portions of the sun canopy. None of the broken lines form part of the claimed design.
